Robert A. Bartlett
BY *J. M. Fowler*,
His ATTORNEY

UNITED STATES PATENT OFFICE.

ROBERT A. BARTLETT, OF WARREN, ONTARIO, CANADA.

STANDARD MOUNTING SOCKET AND CHAIN GRIP.

Application filed January 30, 1928. Serial No. 250,599.

This present invention relates to new and useful improvements in a standard mounting socket and chain grip of the type especially designed for sleighs, wagons, trucks and the like, and has for its primary object, the provision of a device of the character stated which may be readily secured on the bolster or standard supporting beam beneath the body of the sleigh, wagon or truck and the chain extended across the load, firmly secured to the device and held thereby against movement.

The invention has for another object, the provision of a device of the character stated, which is of simple and inexpensive construction, composed of the minimum number of parts and highly efficient in use.

A still further object of the invention resides in the production of a device of the character stated in which the socket is formed of a single blank with integral attaching arms and bearing lugs for the pivots of the bifurcated or bail-like chain holding member.

A still further object of the invention resides in the provision of a device of the character stated, in which the chain holding member is pivotally mounted at the lower inner corners of the socket receiving the standard and swings over the socket and the lower end of the standard therein, to hold the end of the chain back of the standard.

To the accomplishment of these and related objects, as shall become apparent as the description proceeds, my invention resides in the construction, combination and arrangement of parts as shall be hereinafter more fully described, illustrated in the accompanying drawings and pointed out in the claims hereunto appended.

The invention will be best understood and can be more clearly described when reference is had to the drawings forming a part of this disclosure, wherein like characters indicate like parts throughout the several views.

In the drawings:—

Figure 1 is a plan of the blank from which the mounting socket is formed.

Figure 2 is a perspective of the mounting socket and a portion of the chain grip carried thereon.

Figure 3 is a detail section through the mounting socket and the chain grip, showing the same in use, the post being illustrated by dotted lines.

Figure 4 is a detail fragmentary view, showing more clearly the locking staple of the chain grip.

Figure 5 is an elevation of a portion of a sleigh with the invention in use thereon.

Figure 6 is a fragmentary elevation showing a slightly modified form of the invention.

Referring more in detail to the drawings, it is to be noted that the device includes a socket 11 of rectangular form in cross section or plan produced from the blank 12, shown in Figure 1, and which is bent along the parallel lines 13 with the vertical side portions 14 of the blank overlapping to form the outer side of the socket 11 and secured together by appropriate means such as the rivets 15, as illustrated in Figures 2 and 3. The vertical side portions 14 of the blank are extended above the remainder of the body of the blank to increase slightly the outer side of the socket 11, as will be readily understood by referring to the drawings and thus serve as a better receiving and supporting socket for the standard 16. The blank 12 also has extended from its upper and lower edges the gradually tapering extension arms 17 which are secured over the upper and lower faces of the transverse supporting beam 18 beneath the body 19 of the sleigh, wagon, truck or the like, and which is illustrated in Figure 5 as a sleigh, the beam 18 being located above the sleigh runners 20.

Appropriate fastening members 21 such as bolts or the rivets shown in Figure 3, are employed for attaching the socket 11 to the beam 18 and are illustrated as extending through the beam 18 and the extension arms 17 of the socket blank 12. Adjacent one of the extension arms 17, preferably the lower one, are a pair of bearing lugs 22 extended from the main portion of the blank 12 and adapted to be bent at an angle to the main portion of the blank 12 and serve as bearing brackets.

forwardly of the lower inner corners of the socket 11, and within the pocket 23 provided by cutting away the lower outer corner of the beam 18, as shown clearly in Figure 3. The bolt 24 is extended through the bearing lugs 22 and spacing collars or sleeves 25 are positioned on the ends of the bolt 24 outwardly of the bearing lugs 22.

The opposite legs of the bifurcated chain holding member 26 are mounted on the bolt 24, between the heads thereof and the spacing collars or sleeves 25. The chain holding member 26 swings on the bolt 24 over the socket 11, and the standard 16 mounted therein and the chain 27 passed over the load in the body 19, is brought over the edge of the body 19 back of the standard 16 and passed through the chain holding member 26. The retaining or locking staple 28 is passed 20 transversely over one link of the chain 27, after the latter has then drawn through the chain holding member 26 and tightened therein, the legs of the staple 28 extending transversely across the chain holding member 26 and binding against the outer face of the bight portion thereof to hold and lock the chain firmly in position and prevent loosening of the chain 27 by sliding of the latter out of adjusted position in the chain holding member 26.

In the modified form of the invention shown in Figure 6, the members 26 and 28 are dispensed with and, in place thereof there is provided a crotched chain 29 mounted by 35 opposite ends on the bolt 24 and carrying at its central portion the ring 30 through which the chain 27 is extended and held in adjusted position therein by appropriate means such as a hook 31 carried either by the ring 30, as 40 shown in Figure 6, or by the chain 27. It is also to be seen that the chain 29 is illustrated as being formed of two sections connected by the ring 30, although this may be altered as desired. An advantage of the 45 form shown in Figure 6 over the first form resides in the flexibility of the crotched chain 29 which may operate more freely over the socket 11 and the end of the beam 18 or bunk when the device is in use. Furthermore 50 the crotched chain 29 will rest more easily on the socket 11, instead of swinging downwardly when not in use or when not held up by the chain 27 secured thereto.

As the construction of the device has thus 55 been described in detail, brief reference is now had to its use and modus operandi: The device is secured on the beam 18, as illustrated, and the standard 16 mounted in the socket 11. After the chain 27 is extended 60 over the load, the end of the chain 27 is extended through the chain holding member 26, in the preferred form of the invention, and the staple 28 engaged over the chain link passing through the member 26, to bind 65 against the bight portion of the latter and

thus grip the chain 27 in its tightened position over the load, and back of the standard 16, as clearly shown in Figures 3 and 5 of the drawings. Before the chain can be released and removed from the load, the staple 28 must be withdrawn from over the chain 27. It may also be stated at this time that the standard 16 is firmly supported in position, owing to the construction and mounting of the socket structure. Furthermore, the socket 75 structure also serves to provide a firm and strong support for the chain holding member 26 working thereover, on the bolt 24.

In the modified form of the invention shown in Figure 6, the chain 27 is passed 80 through the ring 30 and secured in its adjusted position therein by the hook 31 or other appropriate means as previously stated. This is the main difference between the modus operandi of the second form and 85 the first form of the invention.

From the foregoing description taken in connection with the accompanying drawings, it will be manifest that a standard mounting 90 socket and chain grip is provided that will fulfil all the necessary requirements of such a device, but as many changes could be made in the above description and many apparently widely different embodiments of my invention constructed within the scope of the 95 appended claims without departing from the spirit or scope thereof, it is intended that all matters contained in the said accompanying specifications and drawings, shall be interpreted as illustrative and not in a limited 100 sense.

Having thus described my invention what I claim as new and desire to secure by Letters Patent is:—

1. A standard mounting socket formed of a blank having extensions on opposite edges adapted to be brought into parallel relation and secured on opposite faces of a supporting beam, and bearing lugs provided on opposite portions of said blank for supporting a bail-like chain holding member. 105

2. A standard mounting socket formed of a blank having extensions provided on its upper and lower edges for mounting on opposite faces of a beam end, the body of the blank being bent to provide a standard receiving socket of rectangular form in plan, and bearing lugs provided on said blank at the lower inner corners of the socket to support a bail-like chain holding member working over the said socket. 115

3. As a new article of manufacture, a standard mounting socket formed from a rectangular blank with central tapering extensions along its longitudinal wide edges 125 and adapted to be bent at right angles to the body of the blank in parallel relation for mounting on opposite faces of a beam end; said blank also having a pair of bearing lugs projecting from one of its longitudinal wide 130

edges on opposite sides of the central extension thereof to provide means at the lower inner corners of the socket to support a bail-like chain holding member working over the
5 said socket; the entire body portion of the blank being adapted to be folded on itself with opposed edges overlapping to complete the formation of the socket.

In testimony whereof I hereunto affix my
10 signature.

ROBERT A. BARTLETT. [I. S.]
